UNITED STATES PATENT OFFICE.

OTTO B. SHULHOF, OF NEW YORK, N. Y.

LUMINESCENT ADVERTISING SIGN.

Application filed August 11, 1927. Serial No. 212,157.

My invention relates to that class of signs in which the letters are illuminated by tubes filled with conductive gases and more particularly to signs of this character in which the letters are individually formed and are interchangeable and removable.

At the present time signs formed of glass tubes filled with conductive gases, ordinarily neon gas and other gases which give various colors upon passage of electric current, are in use. In such signs, however, the entire legend is formed of a single tube and cannot be changed without replacing the sign in its entirety. They are, moreover, limited in the style of lettering which can be employed. The most successful of such signs are those that consist of a single tube forming words spelled out in cursory script. Roman or block lettering is difficult to produce in the signs at present in use. Also the method of mounting the tubes is such as to occasion breakage unless very carefully handled.

It is an object of the present invention to furnish luminescent signs which are adaptable to any style of lettering and in which each individual letter consists of a separate tube. It is a further object to provide such signs having letters which are removable and replaceable, or, which may be transposed as desired.

In applying my invention, I employ a separate panel for each letter, said panel being preferably of insulating material such as bakelite, but wood or metal may be used. Upon this panel a letter of the style desired is formed preferably of the same material as the panel is superposed. Through the center of each stroke or bar of the letter, a groove or channel is made to run lengthwise of the stroke or bar of said letter. This channel is adapted and arranged to accommodate the luminescent tube which is shaped to conform to the letter and which may be fastened therein by thin hoops or bands anchored in the material on either side of said channel. The margin of the superposed letter on either side of the channel in which the luminescent tube is placed may be beveled to said channel, the beveled surface being high on the outside edges of the letter and sloping down to the channel. This beveled surface may be painted or enameled in a color harmonizing with that of the gas in the tube when luminescent. At the portion of the superposed letters where the ends of the luminescent letter

come in the channel, openings entirely through the panel are provided so that the ends of the luminescent tube in which the electrodes are placed may protrude through and extend behind the panel within a casing. The casing or cabinet is provided on one side with an opening of sufficient size to accommodate the panels that spell the desired word or words. This opening is furnished with slots along the upper and lower sides thereof and the panels are slid into these in proper order and so held. Within the casing or cabinet, into which the electrodes of each panel protrude the unsightly electrical connections are made and being wholly enclosed are not seen. As luminescent tubes require a very high voltage, a suitable transformer may also be placed within the cabinet and suitable connections made therefrom with an external source of electric current and with the electrodes at the back of the panels.

The invention may be more clearly understood from the drawings in which Fig. I shows a simple panel containing a letter of the invention. Fig. I^A is a section through A—A of Fig. I. Fig. II shows the same panel in sectional elevation with the electrodes and the electrode shells in place. Fig. III shows in perspective a complete sign of the invention set in its cabinet and Fig. IV, is a sectional elevation thereof showing the transformer in place within the cabinet. Fig. V shows partly diagrammatically the system of electrical connections serving a sign of the invention.

Referring now to Fig. I and Fig. I^A, a letter, *a*, composed preferably of an electrically insulating material such as bakelite, is superimposed upon the panel, *b*, of the same material. The letter itself in the form shown is high at the edges, *c*, and beveled down to a channel, *d*, running through the center of said letter. In this channel a luminescent tube, *e*, formed in the shape of the letter is placed and held tightly therein by the rings, *n*. This luminescent tube is filled with a conductive gas, such as neon, and its electrodes are bent back and protrude through the openings, *f* and *f'*, at either end of the letter. It will thus be observed that the somewhat unsightly electrodes and their connections are out of sight of a person looking at the sign. A suitable shell or casing may be employed to cover this electrode and to that end may be fastened at the back of the panel

as a protection against breakage of the electrode chamber or of the tube where it passes through. Such a shell is shown in Fig. II at *g*, and may be of the form described and claimed in my copending application, Serial No. 211,956.

Fig. II which is a sectional elevation of the panel shows the edge of the letter, *c*, raised above the level of the panel, *b*. The luminescent tube, *e*, with its electrode chambers, *h* and *h'*, are shown in dotted lines, the latter extending through the panel and enclosed in the electrode shells, *g* and *g'*.

In Fig. III the method of mounting these panels in the sign is illustrated. An enclosed cabinet or casing, *i*, is employed to house the panels and electrical connections thereof. In the front of said cabinet an oblong opening of sufficient size to accommodate the number of panels needed to spell the desired word is provided with slots, *k*, and *k'* at top and bottom thereof. Into these slots the panels are placed and each letter slid into its proper position.

In Fig. IV the cabinet is shown in sectional elevation with the panel, *b*, in position in the slots *k* and *k'*. The electrodes, *g* and *g'*, extend within the cabinet. A transformer indicated at *l*, adapted to raise the voltage of the current sufficiently to operate the luminescent tubes of the sign is also placed within the cabinet and connected with an external source of electric current by the lead wires, *m* and *m'*.

It will be observed that by mounting a luminescent tube in the groove or channel as described and binding it there tightly with the thin bands, *n*, there is little or no strain exerted upon the tube or its mountings. The tube is further protected by placing the electrode shells over the ends of the tube containing the electrodes where they protrude through the back of the panel.

The electrical connections of a sign of this invention are illustrated in Fig. V which represents the back of the sign. Each letter has two electrodes, one at each end of the luminescent tube forming the light giving element of the letter, and indicated at *o*. Insulated wires, *p*, connect one of the electrodes of one letter with one of the electrodes of the next letter. The connections, *r*, and *s*, lead to the transformer, *t*, which in turn is connected with a source of electric current as indicated.

This is a considerable improvement over the present art in which it is customary when mounting luminescent tubes upon a sign to support them on posts away from the surface of the sign board on which they are mounted or as is done in some cases to support the entire tube by its electrodes. This latter arrangement subjects the tubes to a strain which frequently results in breakage or leakage.

Having thus described my invention what I claim is:—

1. A sign comprising a plurality of panels, a letter form superimposed on each panel, a beveled and grooved channel running centrally through each letter form and conforming to the shape thereof, said groove being at the apex of the beveled channel, luminescent lighting means mounted in the groove of each channel, a housing having slotted opening on one side thereof into the slots of which said panels are placed so as to form words and a transformer and electrical connections therefor, connecting said transformer with an external source of electrical current and with the luminescent lighting means of each panel, said transformer and said connections being positioned within said housing.

2. In a sign, a panel having a letter form superimposed thereon, a beveled and grooved channel centrally positioned in said letter form and conforming to the shape thereof, said groove being at the apex of the beveled channel, a luminescent tube positioned in said groove, means for holding said luminescent tube snugly in said groove, openings through said letter form and said panel adapted and arranged to permit the electrodes of said luminescent tube to project through said panel whereby the electrical connections of said luminescent tube may be made at the back of said panel.

3. In a luminescent sign, means for mounting a luminescent tube comprising a panel of electrically non-conductive material, a form superimposed thereon consisting of the same material, said form being in the shape of a letter the surface of which is beveled down towards the center of each bar of said letter, a groove at the lowest part of said beveled surface adapted and arranged to receive said luminescent tube and holes through said letter form and said panel adapted and arranged to receive the electrodes of said luminescent tube.

4. The combination in a letter for signs, of a panel upon which is fixed a member having the shape of a sign character, a grooved and beveled channel in the character member adapted to seat a luminescent tube of like conformation, said groove being at the apex of the beveled channel each of the extremities of said tube extending backwardly through both the character member and the panel, electrodes on each of said tube extremities and electrode shells covering said electrodes and affixed to the back of said panel.

5. In a sign, the combination of a plurality of abutting panels, each of which carries a member having the shape of a sign character having a beveled and grooved channel in which is seated a luminescent tube of like conformation, said groove being at the apex of the beveled channel the extremities of each of said tubes extending backwardly through both its character member and panel, electrodes on the extremities of each of said tubes,

electrode shells covering said electrodes and affixed to the back of said panel and means electrically to connect all of said tubes in series.

5 6. The combination in a letter for signs of a panel upon which is superimposed a character; said character having a beveled and

grooved channel of like contour wherein the groove of the channel is located at the apex of the beveled channel and is adapted to receive 10 an illuminating tube.

In testimony whereof I have hereunto subscribed my name this 1st day of August, 1927.

OTTO B. SHULHOF.
